[54] METHOD FOR SYNCHRONIZING SETS OF INTERACTING PROCESSES

[51] Int. Cl.² G06F 9/00
 [52] U.S. Cl. 364/300

[75] Inventor: William Wilkinson Collier, Wappingers Falls, N.Y.

[57] ABSTRACT

[73] Assignee: International Business Machines Corporation, Armonk, N.Y.

Allows a set of processes to operate cyclically on a set of shared resources (e.g. I/O buffers). Each process is allowed to proceed at its own speed, subject only to a synchronization condition that it does not operate simultaneously on a resource with any member of the next (cyclic) subset of processes.
